MECHANICAL PENCIL WITH BOTH STEP-BY-STEP AND GRAVITY FEEDS

John T. Brubaker, Luray, Va.

Application May 8, 1946, Serial No. 668,106

8 Claims. (Cl. 120—9)

1

This invention relates to a pencil wherein the lead or marker is held, manipulated and fed in such manner as to overcome the present liability to breakage and with greater assurance of positive feeding.

A second object is to provide a construction wherein the lead or marker may be fed by a step-by-step movement or by gravity.

An object is to so construct the pencil that the operating parts may be readily applied to and removed from the barrel, being made in one or two units preferably insertable and removable from the top of the barrel and the latter, if desired, being sectional to facilitate such insertion and removal.

Various additional objects and advantages will become apparent from a consideration of the description following, taken in connection with the accompanying drawings illustrative operative embodiments by way of example.

In said drawings:

Figure 1 is a central longitudinal sectional view through one form of the pencil constructed in accordance with the invention;

Figure 2 is a longitudinal sectional view taken approximately centrally and looking towards the left in Fig. 1;

Figure 3 is a longitudinal sectional view taken approximately centrally and looking towards the right in Figure 1;

Figure 4 is a cross-sectional view taken on the plane of line 4—4 of Figure 1;

Figure 5 is a cross-sectional view taken on the plane 5—5 of Figure 1;

Figure 6 is a cross-sectional view taken on the plane 6—6 of Figure 1;

Figure 7 is a fragmentary perspective view of one form of lead gripper;

Figure 8 is a central longitudinal sectional view taken through a modified form of pencil;

Figure 9 is an approximately central longitudinal sectional view looking towards the right in Figure 8;

Figure 10 is a cross-sectional view taken on the line 10—10 of Figure 8;

Figure 11 is a cross-sectional view through a modified form of lead magazine;

Figure 12 is a cross-sectional view through a further modified form of lead magazine;

Figure 13 is a central longitudinal sectional view through another modified form of pencil;

Figure 14 is an approximately central longitudinal sectional view looking toward the left in Figure 13;

Figure 15 is an approximately central longi-

2

tudinally sectional view taken through a final form of pencil; and

Figure 16 is a cross-sectional detail taken on the line 16—16 of Fig. 15.

Referring specifically to the drawings, wherein like reference characters designate like or similar parts throughout the different views, 10 designates a barrel or casing preferably tapered as at 11 toward the writing end, and which barrel is preferably made sectional as by having a cap 12 at its upper end detachably screw-threaded or otherwise secured as at 13 to the barrel proper, this separable feature enabling the interior part or parts to be readily positioned, inspected or removed.

Disposed centrally and longitudinally of the barrel 10 as by detachably screwing it into the lower end of the pencil by screw-threads 14 or any equivalent, is a tube 15 to operatively position the lead.

Within the barrel 10 is a magazine 16 which may be cylindrical of any desired shape in cross-section, shown of a size and shape to best accommodate two leads or markers 17, although it may be constructed of a size and shape to contain any desired number. The magazine 16 has a head or base wall 18 provided with a hub 19 into which the lead tube 15 extends, such magazine being a plunger and slidable within the barrel 10 and on said lead tube 15. Leads are supplied to the magazine 16 through an upper end which is normally closed by a head 20 detachably telescoped into the magazine, and which has an outwardly extending flange 21 overlapped by the inwardly extending flange 22 of the barrel cap 12. A head 20 preferably carries a rubber or other eraser 23.

Any suitable abutment means is provided on the interior of barrel 10 at 24 or on the tube 15 and an expansive coil-spring 241 rests thereon and bears against the base 18, thus urging and normally maintaining the flanges 21 and 22 in contact.

The head 20 carries a lead-confining and positioning spring 25 tensioned so as to normally occupy the position shown in Fig. 1 wherein its lower end is disaligned with the bore of the feed tube 15, thus confining a lead as shown, out of alignment with the bore tube and supported on the base 18. However, when a lead is to be fed to the tube 15, the spring 25 is displaced across the bore of the feed tube 15 by sliding a plunger or the equivalent 26 inwardly, such plunger being slidably mounted by a plug 27 detachably screwed or otherwise secured to the barrel 10.

and having a movement relatively thereto limited by an exterior button 28 and interior stop 29.

The lead in tube 15 is frictionally held in place by the engagement of a gripper 30 therewith, the gripper being carried by the tube 15, for instance secured to an enlargement 31 thereon, and extending through a slot 32 in the side of the feed tube.

Attention is also directed to the fact that in addition to the lead gripped by the gripper 30, it is gripped or engaged by another gripper 33 depending from the hub 19 and having a gripper portion 34 extending through an elongated slot 35 in the feed tube. Said grippers 30 and 34 preferably are all V-shaped at their gripping portions as in Fig. 7, so as to provide a plurality of points 36 to engage the lead at spaced locations, better friction thereby being secured and danger of relative slippage of the lead and grippers overcome. Gripper 33 is adapted to be moved to lead releasing position through the engagement of an extension 37 thereon with a cam on the enlargement 31.

In operating the pencil described, while the lead in the feed tube is held by the gripper 30, hub 20 may be depressed by means of short strokes in order that the gripper 34 will engage the lead and feed it against the frictional contact of gripper 30 therewith, a number of short strokes being used, if desired. If the lead is to be released from the feed tube, as in the case of a short used lead, so as to fall by gravity from the feed tube, a longer depression or stroke is imparted to the head 20 in which extension 37 engages the cam surface 38, thereby releasing the lead, after which a rod 40 carried by the hub 19 and extending slidably through the enlargement 31, engages the inclined part 41 of gripper 30, thereby deflecting the same and disengaging the lead, the lead thus being released by both grippers 30 and 34 and being free to slide by gravity from the feed tube.

Attention is called to the fact that the feed tube and leads are of such length that with the grippers 30 and 34 retracted as just described and the pencil inverted, a lead will fall by gravity from the feed tube entirely into the magazine 16, following which the plunger 26 may be operated to displace the partition 25, and upon again positioning the pencil with the pointed end lowermost, and the pencil shaken or tilted somewhat, another lead is aligned with the feed tube and permitted to slide into the same into operative position where it will be engaged by the grippers 30 and 34, if desired, the pointed end of the pencil being held relatively close to a support to prevent any danger of the lead completely sliding out of the feed tube before engagement by the grippers 30 and 34.

The operation mentioned is particularly advantageous where two leads are employed of different colors or shades. This action is further facilitated by having the magazine relatively flat in cross-section, and for instance rectangular as best shown in Fig. 4 since the leads will be bound to move readily, and when the position or location of one lead is known, to make a change to the other lead or color simply requires rotation of the pencil 180° accompanied by operation of the grippers, tilting, inversion and the like to properly position the lead. This same result may be attained where the magazine is not truly rectangular in cross-section, for instance the magazine as shown in Fig. 11, may have its main walls 42 arcuate and concentric. Again the same

result may be attained where the magazine as in Fig. 12 is of 8-shape in cross-section providing the charge chambers 43 and the constricted passage 44, which assists in straightening and positioning the lead when aligned with the feed tube.

The grippers 30 and 34 need not be of the specific construction and mounting shown since they may be secured to any desired parts and positioned as preferred. It will also be noted that practically all of the parts may be removed as a unit from the barrel upon detaching the cap 12 and unscrewing the tube from the barrel at 14. Also the various parts may primarily be made of metal, although they may be constructed of any of the plastics or otherwise, or of a combination of metal and plastic. Where plastic material is used, desired parts can be transparent so that the interior action and position of the leads in particular may be observed from the exterior.

If desired, spring 241 may be dispensed with and the pencil operated by shaking the same, resulting in successive impacts of the sliding magazine body 16 with the barrel, the impacts being controlled so that grippers 34 and 30 operate on the lead as previously described.

As to the modified form of Figs. 8 and 9, the barrel is designated 45 having a detachable pointed or tapered lower end 46 telescoped or otherwise secured at 47 to the barrel. A lead feed tube 48 is detachably screw-threaded or secured at 49 to the part 46 so as to slidably receive and hold the lead 50. Lead tube 48 is removable and at the upper end carries a disk or head 481. The lead tube has a slot 51 in its side through which a gripper 52 extends into engagement with the lead 50, which gripper is carried in any suitable way by the feed tube 48 or any other part as by an enlargement at 52. The gripper in this form of the invention may be disengaged by the gripper 52 by sliding a rod 53 inwardly, such rod being accommodated in an opening 54 of the barrel and having a bifurcated part 55 extended around the feed tube and soldered or otherwise connected to the gripper 52, thus causing the gripper to release the lead.

The lead magazine in this form of the invention is shown at 56 and is closed with the exception of an outlet opening 57 in its bottom wall normally disaligned with the bore of the feed tube, but which is adapted at times to register with such bore, to enable the lead 50 when released by the gripper 52 either to return to the magazine through the opening 57 when the pencil is inverted, or lead to fall by gravity from the magazine through the opening 57 into the feed tube 48. The magazine 56 is suspended normally in the position shown in Fig. 8 by a leafspring 58, and such spring is engaged by a push-rod 59 slidably mounted in a detachable plug 60 screw-threaded in the barrel, such push rod being of the same construction as that described at 56. Spring 58 normally holds the magazine 56 in the position shown, and alignment of the opening 57 with the bore of feed tube 48 is effected by pushing the rod 59 inwardly.

Spring 58 is attached to any suitable part, but preferably is carried by a head or plug 61 detachably screw-threaded at 62 into the upper end of the barrel 45, which further is preferably equipped with a rubber or other eraser 63.

Magazine 56 may be rectangular in cross-section as in Fig. 4 or may have the cross-sectional shapes of Figs. 11 and 12 since this form of the magazine as shown in Fig. 11, may have its main walls 42 arcuate and concentric. Again the same

dating any desired number of leads is well adapted for use with two leads of different colors, as in the first form described, and which leads may selectively be positioned in the feed tube 48 as described with respect to the first form.

Referring now to Figs. 13 and 14, another modified form is shown. This form employs except as slightly modified when so described, a barrel 45, feed tube 48, leads 50, enlargement 521, gripper 52, screw-threads 49, push rod 53, and detachable end section 46 as described in the next preceding form. Accordingly the same reference characters have been applied.

In this form, feed tube 48 carries a head 64 having a central flared bore 65 to guide the leads 50 into the flat tube 48. Preferably two leads are employed, although any desired number may be used, each lead being retained within a holder 66 open at the lower end and normally held disaligned with the opening 65 by means of spring brackets 66 fastened thereto as at 67 and depending from a head 68 removably secured to the upper end of barrel 45 which, in this instance, have exterior screw-threads 69 engaged by the screw-threads of a cap 70, the head and cap having overlapping flanges as shown and the cap preferably carrying a rubber or eraser 71. The tubes 66 are adapted to be swung inwardly selectively to align their lower open ends with the opening 65 to receive or discharge a lead, according to whether or not the pencil is in normal position or inverted. The displacement and alignment of the holders 66 is effected by sliding push rods 72 inwardly, such push-rods being of the same construction as those described at 26 and 59 and being mounted by detachable screw or other plugs 73.

In the final form of the invention disclosed in Figs. 15 and 16, the structure and operation is similar to that of the next preceding form, with the exception of the holding and feeding of the leads, corresponding reference characters accordingly having been applied to corresponding parts. The barrel equivalent to 45 is here designated 74, and at the upper end is closed by a detachable plug 75 screw-threaded or otherwise secured at 76 to the barrel and preferably carrying a lead or eraser 71. Depending centrally from the plug 75 is a stop 78 of any desired length and preferably generally of ovoid form at the lower end and equipped with any desired number of longitudinally extending grooves 79, two for instance as shown. In such grooves, the lower ends of the leads 50 are retained under the pressure of spring fingers 80 which are secured at 81 to the exterior of the barrel 74, then extended inwardly through the slots 82 in the barrel and returning to the exterior and terminating in manually engageable fingers 83. It will be understood that the desired finger 83 may be engaged and pulled outwardly in order to release any desired lead 50, and that by tilting the pencil, the lead will register with the opening 65 and slide by gravity into the feed tube 48, it being advisable as in all other forms, to release the grip on the lead in the feed tube 48, and when the pencil is inverted, enabling the lead to slide back into or return into the upper end of the barrel to the desired slot or groove 79 and be held therein by the fingers or clasps 80.

It will be clear that in all of the forms as described with respect to the first one that the various parts aside from the leads or markers may be made of metal, plastic, transparent or otherwise, or a combination thereof. It will also be clear that in all of the forms the grippers may be

secured to any accessible adjacent part and that they are preferably engageable with the lead at a plurality of points and those of the general construction shown in Fig. 7.

5 Various changes may be resorted to provided they fall within the spirit and scope of the invention.

What is claimed is:

1. A pencil having a barrel, a feed tube therein for a lead, a gripper constantly engaging and normally retaining the lead in said tube, a second gripper for the lead, a depressible plunger means surrounded by the barrel and exposed at the top of the barrel operable in the bore of the barrel to impart feed strokes to the second gripper notwithstanding engagement of the lead as aforesaid by the first gripper, said grippers constituting the sole means affecting free sliding of lead into or out of the pencil through said tube, and mechanism operable upon further depression of the plunger means to selectively release either the first-mentioned gripper or both of said grippers.

2. A pencil having a barrel, a feed tube screw-threaded to the writing barrel at said end and extending interiorly thereof, a head interposed between the top of the feed tube and the inner wall of the barrel, an enlargement on said tube between said head and screw-threads, said tube having a slot between said screw-threads and said enlargement, and a lead-gripping member carried by said enlargement and extending into the tube through said slot.

3. A pencil according to claim 2 having means extending between said tube, enlargement and gripping member and movable against the latter to move it to lead-releasing position.

4. A pencil having a barrel, a feed tube for a lead secured in the barrel against sliding movement, a gripper constantly engaging and normally retaining the lead in said tube, a second gripper for the lead disposed above the first gripper, means operable to impart feed strokes to the second gripper notwithstanding engagement of the lead as aforesaid by the first gripper, said grippers constituting the sole means affecting free sliding of lead into and out of the pencil through said tube, and means operable to release both of said grippers through and after predetermined movement of the second gripper.

5. A pencil having a barrel, a lead feed tube secured to the barrel against relative sliding movement, a plunger within the barrel slidably mounted on the feed tube, means biasing the plunger away from the writing end of the pencil, said feed tube having first and second slots, gripper means extending through the first slot positioned to constantly engage a lead therein, gripper means movable with the plunger extending through the second slot and engageable with a lead in the tube to feed such lead notwithstanding engagement as aforesaid by the first gripper means.

6. A pencil having a barrel, a lead feed tube secured to the barrel against relative sliding movement, a plunger within the barrel slidably mounted on the feed tube, means biasing the plunger away from the writing end of the pencil, said feed tube having first and second slots, gripper means extending through the first slot positioned to constantly engage a lead therein, gripper means movable with the plunger extending through the second slot and engageable with a lead in the tube to feed such lead notwithstanding engagement as aforesaid by the first gripper means.

ing engagement as aforesaid by the first gripper means, the second-mentioned gripper means having a predetermined movement relatively to and independently of the second gripper means.

7. A pencil having a barrel, a lead feed tube secured to the barrel against relative sliding movement, a plunger within the barrel slidably mounted on the feed tube, means biasing the plunger away from the writing end of the pencil, said feed tube having first and second slots, gripper means extending through the first slot positioned to constantly engage a lead therein, gripper means movable with the plunger extending through the second slot and engageable with a lead in the tube to feed such lead notwithstanding engagement as aforesaid by the first gripper means, the second-mentioned gripper means having a predetermined movement relatively to and independently of the second gripper means, means to release the second-mentioned gripper means after predetermined movement, and means to thereafter release the first-mentioned gripper means.

8. A pencil having a barrel, a lead feed tube

therein secured to an end of the barrel, an enlargement on the feed tube, said tube having a slot located between said enlargement and said end, a lead-gripping member carried by said enlargement and extending into the tube through said slot, and a movable element terminally located between said enlargement, tube and gripping member operable from the exterior of the pencil to disengage the gripping member from the lead.
